(57) **CLAIM**

The ornamental design for the display-sales stand, as shown and described.

DESCRIPTION

FIG. 1 is a front perspective view of a display-sales stand in accordance with my new design in a closed configuration;

FIG. 2 is a right side elevation view thereof;

FIG. 3 is a left side elevation view thereof;

FIG. 4 is a rear perspective view thereof;

FIG. 5 is a top plan view thereof;

FIG. 6 is a bottom plan view thereof;

FIG. 7 is a top perspective view thereof;

FIG. 8 is a right side elevation view thereof with the display-sales stand in an open configuration; and,

FIG. 9 is a rear perspective view thereof with the display-sales stand in an open configuration.

The broken lines shown in all figures are for illustrative purposes only and form no part of the claimed design.
